DESIGN FOR A BOTTLE

Henry A. Marks, Cincinnati, Ohio, assignor to Kolmar, Inc., Cincinnati, Ohio, a corporation of Ohio

Application September 17, 1936, Serial No. 64,888

Term of patent 3½ years

To all whom it may concern:

Be it known that I, Henry A. Marks, a citizen of the United States, residing at Cincinnati, Hamilton County, Ohio, have invented a new,
original, and ornamental Design for a Bottle,
of which the following is a specification, reference being had to the accompanying drawing, forming a part thereof, and in which:

Fig. 1 is a top plan view of a bottle showing my new design.

Fig. 2 a face view;
Fig. 3 a side view; and
Fig. 4 a rear view thereof.

I claim:

The ornamental design for a bottle as shown.

HENRY A. MARKS.
